UNITED STATES PATENT OFFICE.

JACOB RZADKOSZ, OF MILLSBORO, PENNSYLVANIA.

DESIGN FOR A CANE OR UMBRELLA HANDLE.

46,780.

Specification for Design.

Patented Dec. 15, 1914.

Application filed July 10, 1914. Serial No. 850,265. Term of patent 7 years.

To all whom it may concern:

Be it known that I, JACOB RZADKOSZ, a subject of the Emperor of Austria-Hungary, residing at Millsboro, in the county of Washington and State of Pennsylvania, have invented a new, original, and ornamental Design for Cane or Umbrella Handles, of which the following is a specification, reference being had to the accompanying drawing, forming part thereof.

Figure 1 is a perspective view looking toward one side, and Fig. 2 is a perspective view looking toward the other side, showing my new design.

I claim:

The ornamental design for a cane or umbrella handle as shown.

JACOB RZADKOSZ.
